C. A. Snowdon

Inventor
B. F. Nelson

UNITED STATES PATENT OFFICE.

BENJAMIN F. NELSON, OF SANTA MARIA, CALIFORNIA.

CHURN.

SPECIFICATION forming part of Letters Patent No. 374,991, dated December 20, 1887.

Application filed March 28, 1887. Serial No. 232,699. (No model.)

To all whom it may concern:

Be it known that I, BENJAMIN F. NELSON, a citizen of the United States, residing at Santa Maria, in the county of Santa Barbara and State of California, have invented new and useful Improvements in Churns, of which the following is a specification.

My invention relates to improvements in churns; and it consists of the peculiar construction and combination of the various parts for service, substantially as hereinafter fully set forth, and particularly pointed out in the claim.

The object of my invention is to provide a churn that is especially adapted for use in large butter making or working establishments, where it is desirable that improved means shall be provided for reciprocating a vertically-movable dasher by hand-power with great ease and without undue fatigue and labor to the operator or operators, which advantage or desiderata my invention possesses.

A further object of my invention is to provide an improved dasher for acting upon the cream in the churn-body which shall permit the cream to pass freely and readily therethrough upon the upstroke of the dasher and without too great resistance, and thereby render the churning operation easier; to provide means for permitting the churn body or receptacle to be tilted from side to side to permit the butter to be gathered with greater facility, and to improve the churn in minor details of construction, so that it shall be simple, strong and durable, comparatively cheap and inexpensive of manufacture, and efficient in operation.

In the accompanying drawings, which illustrate a churn embodying my invention, Figure 1 is a perspective view. Fig. 2 is a vertical central sectional view on the line $x-x$ of Fig. 1. Fig. 3 is a detached perspective view of the dasher, and Fig. 4 is a like view of one of the operating-levers.

Referring to the drawings, in which like letters of reference denote similar parts in all the figures, A designates the main or supporting frame of my improved churn, which consists, preferably, of the side sills, a , which are secured upon a base-board or connecting-plate, a' , and carry vertical standards or up-

rights a^2 , which are all rigidly and firmly secured together, the upper ends of the standards or uprights being recessed or hollowed out to form the open-ended bearings b , in which are journaled the trunnions or shafts b' of the receptacle or body B. This body B is of any desired or preferred shape—square, rectangular, round, &c.—and it is disposed in a vertical position between the standards or uprights 55 in which its trunnions b' are journaled, as is obvious.

The receptacle is provided with a removable cover, B', having a depending flange or ledge, b^2 , which fits within the upper edges of the body and serves to prevent displacement of the cover, and the cover has a vertical central opening, b^3 , through which passes and reciprocates a vertically-disposed dasher-staff, d , of the dasher D. The lower end of the dasher-staff carries a blade, e , which is rigidly secured thereto and preferably rectangular or square in form, and to this rigid blade e is pivoted or hinged wings e' , which are arranged on opposite sides of the rigid blade, a cross-head, e^2 , 70 being secured to the lower end of the staff d . This staff passes entirely through the cross-head and has the rigid blade e secured directly thereto, and the cross-head extends outwardly from and at right angles to the staff and over 75 the wings, so that they abut against the cross-head during the downstroke of the dasher, and are limited by the cross-head during the said stroke of the dasher. Each of these wings and the rigid blade are provided with transverse apertures or perforations for the passage therethrough of the cream during the downstroke of the dasher, and during the reverse or upstroke of the dasher the wings fall or descend by their own weight or gravity to permit 80 the cream to fall or pass back beneath the dasher without hinderance, and thus decrease the resistance to the upward stroke or movement of the dasher, and consequently ease the operation. The upper end of the dasher-staff 85 is extended through the opening in the churn-cover B', and through the extended upper end of the dasher-staff is passed a pivot pin or bolt, f , which serves to pivotally connect the operating or hand levers F of the churn to the 90 dasher-staff, the said levers being arranged in a horizontal position and transversely across 95

and exterior to the receptacle or body, as shown.

The levers have their handles *f*' arranged on opposite sides of the receptacle or body, so that the operators can stand on opposite sides of the churn to operate the levers thereof by which the dasher is reciprocated, and the free ends of the levers are pivotally connected to vertical arms or supports *G*, which are arranged on opposite sides of the body and carried thereby. The levers are pivoted at their middle or centers to the upper end of the dasher rod or staff by the transverse pin or bolt *f*, which is common to both hand-levers, and their free ends are arranged between the upper bifurcated portions of the vertical arms or supports *G*. These arms are pivoted at their lower or opposite ends in the parallel ears or lugs *h* of brackets *H* by means of transverse pins *h*', secured in the said lugs *h*, and the brackets *H* are secured directly to the receptacle or body *B* by screws, bolts, or other suitable fastening devices.

When the churn is in operation, it is desirable that the receptacle or body shall be held very rigid and firm in its proper upright position, and to carry into effect this object I employ a block or support, *I*, which is fitted beneath the churn body or receptacle, and rests on the base-board or platform of the frame *A*, the width of the support being equal to the space between the bottom of the receptacle and the platform, so that the body is prevented from oscillating movement on its trunnions.

My invention is especially adapted for use in large butter making or working establishments, where it is customary to operate upon large quantities of cream—as, for instance, one hundred gallons at a single operation—and the receptacle is made of such a size as will contain the desired quantity, the levers being proportioned to the power required.

In operation, the cream is first placed in the receptacle and the cover replaced, after which the levers are connected to the dasher staff and the free ends thereof grasped by the operator or operators and moved up and down alternately to reciprocate the dasher and thus act upon the cream to make the butter. After

the operation of churning has been completed, the levers are disconnected from the dasher-staff and thrown to one side on their pivots of the vertical arms or supports, and the cover is removed to permit ready access to the interior of the body to remove the butter. During this operation of removing and gathering the butter the support or block is removed to permit the receptacle to be oscillated from one side to the other on its trunnions, and thus enable the operator to more readily and quickly reach the parts to which the butter adheres and to gather the same.

It will thus be seen that I provide an improved churn which can be operated with comparative ease by hand or manual power, to dispense with horse-power and other motors, and that the device permits of the ready and easy gathering of the butter after the churning has been completed.

The device is simple and strong in construction, not liable to get out of order, and can be manufactured at a comparatively small cost.

Having thus fully described my invention, what I claim as new, and desire to secure by Letters Patent, is—

As an improvement in churning, the combination, with the body, of the brackets secured to the opposite sides of the churn-body, the vertical arms having their lower ends pivoted to the brackets, the dasher-rod, the levers extending across the top of the churn and having a common pivotal connection with the dasher-rod, their outer ends being pivotally connected to the upper ends of the vertical arms, the cross-head *e*', secured to the lower end of the dasher-rod, the dasher *e*, secured to the under side thereof, and the wings *e*', hinged to the opposite side edges of the dasher and limited in their upward movement by the ends of the cross-head *e*', all arranged and operating substantially as specified.

In testimony that I claim the foregoing as my own I have hereto affixed my signature in presence of two witnesses.

BENJAMIN F. NELSON.
